Primary Examiner—Dominic Simone(74) *Attorney, Agent, or Firm*—Lackenbach Siegel, LLP;
Andrew F. Young(57) **CLAIM**

The ornamental design for a shoe sole, as shown and described.

DESCRIPTION

FIG. 1 is a front perspective view of a shoe sole showing my new design.

FIG. 2 is a right side elevational view of the shoe sole of FIG. 1.

FIG. 3 is a left side elevational view of the shoe sole of FIG. 1.

FIG. 4 is a front elevational view of the shoe sole of FIG. 1.

FIG. 5 is a rear elevational view of the shoe sole of FIG. 1; and,

FIG. 6 is a bottom plan view of the shoe sole of FIG. 1.

The broken line showing is for illustrative purposes only and forms no part of the claimed design.
